CAPPED BATTERY OPERATED CAUTERY

David E. Staub, Clearwater, Fla., assignor to
Concept, Inc., St. Petersburg, Fla.

Filed June 9, 1971, Ser. No. 151,622

Term of patent 14 years

Int. Cl. D24—02

U.S. Cl. D83—12 R

FIG.1

FIG.2

FIG.4

FIG.5

FIG.6

FIG.3

FIG. 1 is a top end view of the capped battery operated cautery.

FIG. 2 is a side view of the capped cautery.

FIG. 3 is a bottom end view of the device.

FIG. 4 is a view similar to that shown in FIG. 2, in which the device is rotated through an arc of approximately 45° from that shown in FIG. 2.

FIG. 5 is a distended view similar to that of FIG. 2 showing the cap removed from the cautery; and

FIG. 6 is a distended view similar to that of FIG. 4 showing the cap removed from the cautery.

I claim:

The ornamental design for a capped battery operated cautery, as shown and described.
